Austin G. Edmonson
INVENTOR

UNITED STATES PATENT OFFICE.

AUSTIN GUDMUNDSEN, OF SALT LAKE CITY, UTAH.

LAUNDRY-ASSORTING PIN.

Application filed March 12, 1923. Serial No. 624,387.

To all whom it may concern:

Be it known that I, AUSTIN GUDMUNDSEN, a citizen of the United States, residing at Salt Lake City, in the county of Salt Lake 5 and the State of Utah, have invented a new and useful Laundry-Assorting Pin, of which the following is a specification.

This invention has relation to a quick detachable laundry assorting pin and it consists 10 in the novel construction as hereinafter described.

The object of the invention is to provide an assorting pin which may be easily and effectively fastened to an article or articles 15 of laundry and which will serve as an identification tag and as a hanger for the article or articles of laundry in sorting and from which the article or articles of laundry may be easily, quickly and without injury disengaged therefrom.

In the accompanying drawing Figure 1 shows a front and side view of the pin. Figure 2 is a view of the pin open and holding an article of laundry. Figure 3 is a 25 view of the pin holding an article of laundry and mounted on the assorting rod 6. The bar 7 is arranged alongside the rod 6 and acts as a bank on one side 5 of the pin.

In accordance with my invention I provide a piece of spring wire bent to form a hook 1, one end of which is sharpened to a point. The back portion 4 of the hook extends upwardly and around to form a 30 spring bend 3 and downwardly parallel with the back portion 4 to form one reach of the double side 5, and with a bend 15 therein which engages between the bank 7 and the rod 6; and the wire is then bent at right angles toward the back 4, as at 12, and back upon itself, as at 11, enclosing the said 35 back or shank member 4 and forming the guard 2. The wire is then bent upwardly 40 to conform with the reach 5 and its end fastened by the number plate 8. A separate 45 piece of metal 10 is secured to the sides 11 and 12 to hold them in spaced apart position. From the foregoing arrangement it 50 will readily be seen that as the pin is opened by pressing together the portions 4 and 5 the hook 1 is maintained in alinement with the guard 2, and when the pin is allowed to close by the tension of the spring outwardly

the sharpened end of the hook 1 will recede within the notch or recess 9 of the guard 2 and will be retained therein by the action 55 of the spring 3. The identification number plate 8 may be attached at any convenient point on the pin, preferably on the spring bend 3, as shown.

In practice the pin operates as follows: 60

To fasten the pin to an article of laundry the pin is placed between the thumb and forefinger and compressed so that the hook point 1 is moved against the action of the spring 3 from within the guard 2. The 65 hook point is then forced thru the material of the laundry article and the pin released from between the thumb and forefinger, the hook point receding into the guard.

In removing the article of laundry from 70 the pin after the pin has been placed on the assorting rod, the operation is as follows: Referring to Figure 3, the pin is shown on the assorting rod 6 with the article of laundry to be removed held by the pin on the 75 sharp pointed hook 1. The bar 7 is arranged alongside the assorting rod 6 and acts as a bank to one side 5 of the pin. To remove the article of laundry it is only necessary to pull it to the side toward the bank 80 7. This moves the hook 1 against the action of the spring 3 past the guard 2, exposing the point and thus permitting the cloth to slide from the hook and free from the pin.

Having described my invention what I 85 claim is new and desire to secure by Letters Patent is:

1. A laundry assorting pin comprising a hook with a pointed end adapted to pierce a laundry article; a guard member slidably 90 mounted adjacent to the hook, said guard member having side portions for guiding the back portion of the hook and forming a recess for receiving and protecting the pointed end of the hook; a spring member, 95 one end of which connects to the guard and the other end of the hook, said spring adapted to hold the hook member within the recess of the guard; a number plate attached to the spring member. 100

2. A device of the class described having a substantially hook-shaped pin member with a sharp pointed end; a guard member enclosing the shank of the pin, said guard

also having a notch for receiving and protecting the sharpened end of said hook-shaped pin member, and spaced apart guide portions for guiding the back portion of said pin; a spring formed of a portion of the pin member; and a number plate thereon.

In testimony that I claim the foregoing as my own, I have affixed my signature in the presence of two witnesses.

AUSTIN GUDMUNDSEN.

Witnesses:
